UNITED STATES PATENT OFFICE

HARVEY M. ALLISON, OF WORCESTER, MASSACHUSETTS, ASSIGNOR TO JOHN BATH, OF WORCESTER, MASSACHUSETTS

BACKING OFF MECHANISM FOR GRINDING MACHINES

Application filed March 27, 1931. Serial No. 525,789.

This invention relates to mechanism for use in a machine for grinding taps or similar articles, and provides mechanism for effectively backing off or relieving the teeth of a tap to provide a desired clearance. Mechanism for this general purpose is shown in the prior application of Allison and Walker, Serial No. 381,568, filed July 27, 1929.

It is the general object of my present invention to improve and simplify the mechanism shown in said prior application, making the same more convenient and economical to construct, more easy to adjust with respect to the work, and less exposed to the action of particles of abrasive.

My invention further relates to arrangements and combinations of parts which will be hereinafter described and more particularly pointed out in the appended claims.

A preferred form of the invention is shown in the drawings, in which

Fig. 1 is a plan view of certain parts of my improved mechanism;

Fig. 2 is a detail side elevation, looking in the direction of the arrow 2 in Fig. 1;

Fig. 3 is a diagrammatic plan view, showing the relation of the wheel and work;

Fig. 4 is an end elevation, looking in the direction of the arrow 4 in Fig. 1;

Fig. 5 is a rear elevation, partly in section, and looking in the direction of the arrow 5 in Fig. 1;

Fig. 6 is a plan view of certain parts shown in Fig. 5;

Fig. 7 is a detail side elevation, looking in the direction of the arrow 7 in Fig. 6;

Fig. 8 is a sectional plan view of a driving connection, taken along the line 8-8 in Fig. 4;

Fig. 9 is a sectional plan view of certain eccentric driving mechanism;

Fig. 10 is a plan view of portions of the eccentric driving shaft;

Fig. 11 is a plan view of an eccentric member;

Fig. 12 is a side elevation thereof, looking in the direction of the arrow 12 in Fig. 11;

Fig. 13 is a plan view of a locking collar, and

Fig. 14 is a diagrammatic side elevation, showing the method of setting the work.

Referring to Figs. 1 and 4, I have shown portions of a grinding machine base or frame 20 having longitudinally extending guideways for a work table 21 and a wheel table 22. A grinding wheel G (Fig. 4) is mounted in a wheel head 24 (Fig. 5) which is supported on a wheel slide 26.

The wheel head 24 is adjustable forward and rearward on the wheel slide 26, such adjustment being accomplished by an adjusting screw 27 mounted in the head 24 and threaded in a nut 28 secured in a bracket 29 (Fig. 5) mounted on the slide 26. The screw 27 may be turned manually or automatically for adjustment of the wheel toward or away from the work.

The work W (Fig. 3) may be supported on a work spindle 30 and tail center 31, secured respectively in a head stock 32 and a tail stock (not shown) carried by the work table 21. During the operation of the machine, the work table 21 is reciprocated by means of a lead screw 33 (Fig. 4) and the spindle 30 is rotated through suitable connections to a driving shaft 35 (Fig. 1).

The wheel table 22 may be adjusted longitudinally on its guideways by an adjusting screw 37. This adjustment of the wheel table is commonly used for shifting the wheel to different longitudinal sections of the work and for adjusting the machine to pieces of work of widely different lengths. The table 22 commonly remains fixed in position on the base 20 during the operation of the machine.

I will now describe the mechanism for giving the wheel slide 26 a forward and rearward reciprocating movement for relieving the teeth of a tap or other piece of work.

The wheel slide 26 (Fig. 5) is supported on anti-friction bearings 40 for easy forward and rearward sliding movement on the wheel table 22. A rock shaft 42 is pivotally mounted in bearing arms 43 and 44 projecting rearward from the wheel table 22 (Fig. 2). An arm 45 (Fig. 5) projects upward from the rock shaft 42 and is slotted to receive a cross-rod 46 mounted in brackets 47 and 47 at the rear of the wheel slide 26.

The rock shaft 42 is preferably provided with countersunk bearing surfaces at the ends thereof, which are supported on conical centers 48 longitudinally adjustable in the bearing arms 43 and 44.

A second arm 50 projects upward from the rock shaft 42 and is pivotally connected to a link 51 (Figs. 1 and 2) which extends forward over the wheel table 22 and is provided at its forward end with a bushing 52 (Fig. 9) for an eccentric member 53 which is rotatable therein.

The member 53 has a circular opening 54 (Fig. 12) which fits closely on an eccentric portion 55 (Figs. 9 and 10) of an eccentric shaft 56 which is rotatably mounted in bearings 57 and 58 formed on a bracket 59 (Fig. 4) secured to the top of the wheel table 22. The eccentric member 53 is provided with a flange 60 having notches 61 to which a wrench or spanner may be applied for adjusting the eccentric member.

One outer end of the hub of the eccentric member 53 is serrated as indicated at 62 (Fig. 11), and a collar 63 is provided with teeth 64 corresponding to the serrations on the eccentric member.

The collar 63 is keyed to the eccentric portion 55 of the shaft 56 and is forced against the eccentric member 53 by a lock nut 66. At its opposite end, the eccentric member 53 abuts against a collar 67 interposed between the eccentric member 53 and an enlarged bearing portion 68 of the eccentric shaft 56. The outer end of the shaft 56 is still further enlarged to provide a cylindrical portion 69 of the eccentric shaft 56 and is rotatable therewith. The collar 71 is provided with numbered graduations for a purpose to be described and the collar 63 is similarly graduated.

The driving head 70 is slotted to receive a square shaft 74 and is also recessed to receive the cylindrical end portion 75 thereof. The shaft 74 may be secured in the head 70 by inserting a cross pin 76 (Fig. 9).

The shaft 74 extends through a square axial opening in a sleeve 77 (Fig. 8) rotatable in bearings 78 and 79 formed in a bracket 80 (Figs. 1 and 4) extending rearward from a gear plate 81 mounted on and secured to the head stock 32 (Fig. 1) of the grinding machine.

The middle portion of the sleeve 77 (Fig. 8) is formed as a pinion 84 which is connected by change gears 85, 86, 87 and 88 (Figs. 1 and 4) to a gear 90 on a driving shaft 91. The shaft 91 is also connected through gears 92 and 93 to the lead screw 33 and by additional gears (not shown) to the work spindle 30 (Fig. 3). The eccentric member 53 is thus rotated in a definite speed relation to the work spindle 30 and to the lead screw 33.

By using different arrangements of change gears, the eccentric member 53 may be ro-

tated to advance and withdraw the grinding wheel any desired number of times during each revolution of the tap or other work on the work table. For instance, for the four flute tap shown in Fig. 14 the grinding wheel 70 G will be advanced and withdrawn four times for each revolution of the work.

The square shaft 74 provides a constant driving connection between the sleeve 77 and the eccentric member 53, while at the same time permitting longitudinal reciprocation of the work table 21 and longitudinal adjustment of the wheel table 22.

I have also provided a gauge bar 95 (Figs. 4 and 14) pivoted at 96 on a portion of the work table 21 and having an upwardly projecting end portion 97 offset to provide a shoulder 98 adapted to be swung into the path of the lands of the work W and to engage the upper or cutting edge of the rearmost 85 land.

This gauge bar 95 is used in setting up the machine and the method of using the same is as follows:

The collar 63 (Fig. 13) is graduated to indicate thousandths of an inch in forward and rearward movement of the wheel carriage and grinding wheel. As previously stated, this collar is keyed to the eccentric portion 55 of the eccentric driving shaft 56. 95 To set the machine, the lock nut 66 is backed off, allowing the serrated collar 63 to clear the teeth on the end of the eccentric member 53. The eccentric member 53 is then turned by a wrench or spanner until a zero 100 or index line on the eccentric member 53 corresponds with the index line numbered "5" on the collar 63. The collar 66 is then tightened to lock the parts together in their adjusted relation. When thus locked, the eccentric member 53 will be in such relation to the eccentric portion 55 of the driving shaft 56 that the throw of the eccentric member will correspond to a relieving movement of five thousandths of an inch for the grinding wheel G. 110

It is now necessary to angularly adjust the work with relation to the forward and rearward movement of the grinding wheel, so that the grinding wheel may be at its rearmost position as the cutting edge of each land of the tap arrives in grinding position. 115

To accomplish this result, the gauge 95 (Figs. 4 and 14) is swung into position and the work W is turned on the work centers 120 until the cutting edge of one of the lands engages the shoulder 98 of the gauge, as shown in Fig. 14.

The driving mechanism of the machine is then turned manually until the division 5 on the graduated collar 71 (Fig. 9) comes opposite an index or pointer 100 fixed on the bearing 58. The collar 71 and the serrated collar 63 are secured on the shaft 56 in such angular relation that when the eccentricity 130

is set for five thousandths on the collar 63 and the collar 71 is set to bring the graduation 5 opposite the index 100, the grinding wheel G will be in its rearmost position. The 5 driving dog or chuck is then adjusted to retain the work W in the desired fixed relation to the work spindle 30. The machine is then ready to proceed with the grinding and relieving of the tap.

10 The setting does not ordinarily need to be repeated until another and different lot of taps are to be relieved.

The eccentric member 53 acts to move the grinding wheel positively both toward and 15 away from the work but in order to eliminate any back-lash, a spring 102 (Fig. 7) is mounted between the wheel table 22 and an arm 103 supported by rods 104 extending rearward from the wheel slide support 26. 20 The spring 102 takes up all back-lash which might otherwise develop and prevents the possibility of chatter marks.

The mounting of the rock shaft 42 at the rear of the machine is of substantial advantage over the construction shown in the previous Alison and Walker application, as the parts are much more easily accessible for inspection or adjustment and are also substantially removed from the work and the grinding wheel and are more easily protected from the action of abrasive particles.

Having thus described my invention and the advantages thereof, I do not wish to be limited to the details herein disclosed, otherwise than as set forth in the claims, but what 35 I claim is:—

1. In a grinding machine, a grinding wheel, a wheel head, a wheel slide, a wheel slide support, a rock shaft mounted in bearings at the 40 rear of said support and directly connected to the rear of said wheel slide, an arm on said rock shaft, an eccentric member mounted on said support and rotatable in timed relation to the rotation of the work, and a link extending forward from said arm and above 45 said wheel slide support and having a bearing portion fitting said eccentric member.

2. In a grinding machine, a grinding wheel, a wheel head, a wheel slide, a wheel slide support, a rock shaft mounted in bearings at the 50 rear of said support and having an arm slotted to engage a cross rod mounted in brackets at the rear of said wheel slide, a second arm on said rock shaft, an eccentric member 55 mounted on said support and rotatable in timed relation to the rotation of the work, and a link extending forward from said arm and above said wheel slide support and having a bearing portion fitting said eccentric member.

3. In a grinding machine, a grinding wheel slide, a support therefor, means to reciprocate 60 said slide forward and rearward between predetermined limits on said support, said reciprocating means including a shaft mounted on 65 said support and having an eccentric portion

and an eccentric member mounted thereon, a pair of graduated collars mounted on said shaft, both of which collars being fixed angularly with respect to said shaft and to each other, an index on said eccentric member for one collar, and an index on said support for the other collar, said graduations and indices cooperating to show the range of movement of the grinding wheel and the rearmost position thereof.

4. In a grinding machine, a grinding wheel slide, a support therefor, means to reciprocate said slide forward and rearward between predetermined limits on said support, said reciprocating means including a shaft mounted on said support and having an eccentric portion and an eccentric member mounted thereon, a pair of graduated collars mounted on said shaft, both of which collars being fixed angularly with respect to said shaft and to each other, an index on said eccentric member for one collar, an index on said support for the other collar, and a gauge bar for setting the work in an angular position corresponding to the rearmost position of the grinding wheel 85 as determined by said graduations and indices.

5. In a grinding machine, a grinding wheel a wheel slide, an eccentric driving shaft, an eccentric member angularly adjustable on 90 said shaft to vary the combined eccentric effect, connections between said eccentric member and said wheel slide, and means to indicate the position of said eccentric member which corresponds to rearmost position of 95 said wheel slide.

6. In a grinding machine, a grinding wheel, a wheel slide, an eccentric driving shaft, an eccentric member angularly adjustable on 100 said shaft to vary the combined eccentric effect, connections between said eccentric member and said wheel slide, means to indicate the position of said eccentric member which corresponds to rearmost position of said wheel slide, and means to set the work in a definite 105 angular position corresponding to said rearward position.

In testimony whereof I have hereunto affixed my signature.
